(57) **CLAIM**

The ornamental design for working machine, as shown and described.

DESCRIPTION

FIG. 1 is an upper right perspective view of my design for a working machine;
FIG. 2 is a front elevation view thereof;
FIG. 3 is a left side view thereof;
FIG. 4 is a right side view thereof;
FIG. 5 is a back elevation view thereof;
FIG. 6 is top plan view thereof;
FIG. 7 is a bottom view thereof;
FIG. 8 is an upper right perspective view of another embodiment of my design;
FIG. 9 is another front perspective view thereof;
FIG. 10 is a left side view thereof;
FIG. 11 is a right side view thereof;
FIG. 12 is a back elevation view thereof;
FIG. 13 is a top plan view thereof; and,
FIG. 14 is a bottom view thereof.
